DESIGN FOR A COMBINED TAIL AND DIRECTIONAL LIGHT FOR A BICYCLE

Orlando F. Ingle, Richmond, Ind.

Application April 28, 1947, Serial No. 138,665

Term of patent 14 years

(Cl. D48—24)

To all whom it may concern:

Be it known that I, Orlando F. Ingle, a citizen of the United States, residing at Richmond, in the county of Wayne and State of Indiana, have invented a new, original, and ornamental Design for a Combined Tail and Directional Light for a Bicycle, of which the following is a specification, reference being had to the accompanying drawing, forming a part thereof, and in which

Fig. 1 is a perspective view of a combined tail and directional light for bicycles, showing my new design.

Fig. 2 is a view in end elevation.

Fig. 3 is a view in side elevation, and

Fig. 4 is a top view of my new design.

I claim:

The ornamental design for a combined tail and directional light for a bicycle, as shown.

ORLANDO F. INGLE.
